Primary Examiner — Philip S Hyder*Assistant Examiner* — Cary M Robinson(74) *Attorney, Agent, or Firm* — Finnegan, Henderson, Farabow, Garrett & Dunner LLP(57) **CLAIM**

The ornamental design for a display screen with animated graphical user interface, as shown and described.

DESCRIPTION

FIG. 1 is a front view of a display screen with animated graphical user interface, showing the new design;

FIG. 2 is a front view of a second image thereof; and,

FIG. 3 is a front view of a third image thereof.
The portions depicted in broken dashed lines of uneven length illustrate a boundary and the display screen and the portions depicted in broken dashed lines of even length illustrate portions of the animated graphical user interface. None of the broken lines form part of the claimed design.**1 Claim, 3 Drawing Sheets**(56)
